UNITED STATES PATENT OFFICE

2,539,388

PREPARATION OF AMINOINDANE COMPOUNDS

Milton J. Allen, Baltimore, Md., assignor to the United States of America as represented by the Administrator of the Federal Security Agency

No Drawing. Application November 5, 1948,
Serial No. 58,632

4 Claims. (Cl. 260—578)

(Granted under the act of March 3, 1883, as amended April 30, 1928; 370 O. G. 757)

1

The invention described herein may be manufactured and used by or for the Government of the United States for governmental purposes without the payment to me of any royalty thereon in accordance with the provisions of the act of April 30, 1928 (ch. 460, 45 Stat. L. 487).

This invention relates to the production of new chemical compounds and to processes therefore. More particularly, this invention relates to the production of aminoindanes and aminoindenes from bis-aminophenyl alkyl glycols. This invention also relates to the production of valuable by-products during the production of the above-mentioned indanes.

Heretofore, it was known that certain hydroxy indenes, closed ring analogs of stilbestrol, and certain hydroxy indanes, closed ring analogs of the hexestrol type, possessed estrogenic properties. It has been found that certain amino-phenyl alkyl indeneamines and indaneamines possess estrogenic activity. These can be prepared in a simple fashion from bis-aminophenyl alkyl ethylene glycols. During the course of the preparation, there is usually formed an appreciable quantity of valuable oxo compounds suitable for further conversion into substituted stilbenes.

Accordingly, this invention has for an object the production of 2-(p-aminophenyl)-3-methyl-6-aminoindene and 2-(p-aminophenyl)-3-methyl-6-aminoindane and their corresponding hydrochlorides. A further object of this invention is to produce the above indane and indene compounds from bis-(p-aminophenyl) methyl ethylene glycol dihydrochloride. Another object is to produce as a valuable by-product, gamma-oxo-beta, gamma-(di-p-aminophenyl)-beta-methyl propane. Other objects will be apparent or will appear hereinafter as the ensuing description proceeds.

The foregoing objects are accomplished in accordance with this invention wherein bis-(p-aminophenyl) methyl ethylene glycol dihydrochloride is subjected to a dehydration reaction to yield 2-(p-aminophenyl)-3-methyl-6-indene-amine dihydrochloride, which is then hydrogenated to 2-(p-aminophenyl)-3-methyl-6-aminoindane. During the dehydration, there is concurrently formed from the glycol compound an appreciable proportion of gamma-oxo-beta, gamma-(di-p-aminophenyl) beta-methyl propane which is a valuable intermediate for the preparation of alpha, beta alkyl substituted amino stilbene compounds as described in my co-pending application, Serial No. 58,631, filed on concurrent date herewith.

2

While this invention is not to be limited by any theoretical explanation, the following equations illustrate a reaction mechanism which agrees with data now on hand:

5 Bis-(p-aminophenyl) methyl ethylene glycol dihydrochloride

Dehydration

15 Gamma-oxo-beta, gamma-(di-p-aminophenyl)-beta-methyl propane dihydrochloride

25 2-(p-aminophenyl)-3-methyl-6-aminoindene dihydrochloride

Hydrogenation

35 2-(p-aminophenyl)-3-methyl-6-aminoindane dihydrochloride

Aqueous alkali

45 2-(p-aminophenyl)-3-methyl-6-aminoindane

The starting material for the herein described process, bis-(p-aminophenyl) methyl ethylene glycol dihydrochloride, is prepared from p-aminacetophenone by electrolytic bimolecular reduction as described in my co-pending application, Serial Number 58,630, filed on concurrent date herewith.

50 The dehydration of this invention is carried out by subjecting the aforesaid glycol compound to mildly dehydrating conditions such as, for example, heating a solution of the compound in the presence of acetyl chloride, phosphorous pentoxide, or, preferably, by heating in the presence of dilute aqueous hydrochloric acid. In general, heating a mixture of 10 to 50 parts by weight of bis-(p-aminophenyl) methyl ethylene glycol dihydrochloride with 100 to 300 parts by weight of water and 50 to 150 parts by weight of con-

centrated hydrochloric acid (37%), results in a good dehydration of the glycol compound. As the quantity of water is increased a larger proportion of the glycol compound is converted into gamma-oxo-beta, gamma di(p-amino-phenyl) beta methyl propane dihydrochloride and a smaller proportion of 2-(p-aminophenyl)-3-methyl-6-indeneamine dihydrochloride is formed. With a higher proportion of concentrated hydrochloric acid, decomposition increases with concurrent formation of tarry byproducts.

Heating the mixture of the said glycol compound, water and hydrochloric acid to boiling, under reflux is a preferred method or way to carry out the dehydrating step. In general, one may simply heat the reaction mixture in an ordinary glass reaction flask equipped with a reflux condenser to condense and return evolved vapors to the reaction mixture. As is known to those skilled in the art, this step is generally described as "refluxing" the reaction mixture. The refluxing is continued until the desired 2-(p-aminophenyl)-3-methyl-6-indeneamine dihydrochloride is formed. Thereupon, there is preferably incorporated an additional quantity of concentrated hydrochloric acid and the reaction mixture is chilled in a refrigerator overnight or for several hours. This accomplishes a "salting out" of the crystalline product which under these conditions crystallizes out of the reaction mixture. The crude product in crystalline form is filtered from the cool reaction mixture and preferably recrystallized by dissolving the crude product in a minimum amount of water, filtering the solution, and then adding an equal quantity of hydrochloric acid to "salt out" the crystals again. The purified product is recovered by filtering the crystals from the hydrochloric acid solution. The free base of the indene compound is prepared from the dihydrochloride by dissolving the crystalline indene compound salt in water and neutralizing with a dilute aqueous alkali such as, for example, ammonium hydroxide solution, sodium hydroxide solution, or potassium hydroxide solution. Recrystallization of the free amine from methanol results in the compound 2-(p-aminophenyl)-3-methyl-6-aminoindene, melting at 168-169° C. with decomposition.

The original mother liquor from the dehydration is saved and evaporated to a very small volume, an equal quantity of absolute ethanol is added and chilled to induce crystallization. The crystalline gamma-oxo-beta, gamma-(di-p-aminophenyl)-beta-methyl-propane dihydrochloride is separated by filtration. This compound melts with decomposition at 270-273° C. As described in my co-pending application, Serial No. 58,631, filed on concurrent date herewith, the oxo compound can readily be converted into estrogenic aminostilbene compounds.

After separation of the formed 2-(p-aminophenyl)-3-methylindeneamine dihydrochloride, the said indeneamine compound is hydrogenated to the corresponding indane compound by treating a solution thereof with catalytic or nascent hydrogen. The indene double bond is thereupon saturated to give the indane compound. A suitable way of accomplishing this hydrogenation may be by treatment with gaseous hydrogen in the presence of nickel on kieselguhr, Raney nickel, or the like, but preferably, the indene double bond is saturated by treating the indeneamine dihydrochloride salt with anhydrous normal propanol and sodium metal to yield 2-(p-aminophenyl)-3-methyl-6-aminoindane. In

general, the indeneamine salt is treated with, per part thereof, about 2 to 4 parts by weight of sodium metal and about 40 to 60 parts by weight of normal propanol. After completion of the reaction, which is stimulated by heating under reflux conditions, an excess of water is added to the reaction mixture and the residual alcohol evaporated off. The aqueous mixture is chilled, whereupon the aminoindane compound is precipitated in the form of crystals. The aqueous mother liquor, containing sodium chloride and sodium hydroxide, is removed by filtration, and the aminoindane compound is recrystallized from a suitable solvent, e. g., methanol, to yield a purified aminoindane compound. The product, 2-(p-aminophenyl)-3-methyl-6-aminoindane has a melting point of 162-163° C.

The following illustrative examples show how the invention may be carried out, but it is not limited thereto:

Example I.—Preparation of 2-(p-aminophenyl)-3-methyl-6-aminoindene

28.7 grams of bis-(p-aminophenyl) methyl 25 ethylene glycol dihydrochloride are refluxed for one and one-half hours with 100 ml. concentrated HCl and 200 ml. H₂O. At the end of this period an additional 100 ml. conc. HCl are added and the reaction mixture chilled overnight. The 30 crystals are collected. They can be purified by dissolving in 50 ml. of water, filtering and adding 50 ml. of conc. HCl. Yield 60.7% of theory. The free base upon recrystallization from ethanol melts at 168-169° C. (dec.).

35 Evaporating the original mother liquor to a very small volume and triturating the residue with absolute ethanol gives a 30.8% yield of gamma-oxo-beta gamma di(p-aminophenyl)-beta-methyl propane dihydrochloride, M. P. 40 270-273° C. (dec.).

Example II.—Preparation of 2-(p-aminophenyl)-3-methyl-6-aminoindane

1.2 grams of indene dihydrochloride are re-45 fluxed with 60 ml. n-propyl alcohol to which is added portionwise over a period of one hour 3.6 grams of sodium. After all the sodium is added, the mixture is allowed to reflux for an additional one hour. An excess of water is added and the 50 alcohol evaporated. The aqueous mixture is chilled and indane filtered. After washing and recrystallization from methanol a compound, M. P. 162-163° C. is obtained in 95% yield.

Both the produced aminoindene and aminoindane compounds possess valuable estrogenic properties. Therefore, it will be apparent that new and valuable chemical compounds have been produced in accordance with this invention by a simple process yielding also a valuable by-product.

60 While the invention has been particularly described with reference to the production of methyl substituted aminoindenes and aminoindanes from the methyl substituted glycols, it will be apparent that other substituted indenes such as, for example, ethyl, propyl and the like, may be prepared from the corresponding substituted glycols by the process of this invention.

Since many apparently differing embodiments of this invention will occur to one skilled in the 70 art, various changes can be made therein without departing from the spirit and scope thereof.

What is claimed is:

1. An estrogenic compound selected from the group consisting of 2-(p-aminophenyl)-3-methyl-6-aminoindene, and 2-(p-aminophenyl)-

3-methyl-6-aminoindane and the hydrochlorides thereof.

2. 2 - (p - aminophenyl) - 3 - methyl - 6 - aminoindene.

3. 2 - (p - aminophenyl) - 3 - methyl - 6 - aminoindane.

4. A process for the production of 2-(p-aminophenyl)-3-methyl-6-aminoindane which comprises heating to boiling a mixture of about 50 to 150 parts by weight concentrated hydrochloric acid, 100 to 300 parts by weight of water, and 10 to 50 parts by weight of bis-(p-aminophenyl) methyl ethylene glycol dihydrochloride, and continuing said heating while condensing evolved vapors and returning condensate to said mixture until 2-(p-aminophenyl)-3-methyl-6-indene-

amine dihydrochloride is formed, then treating the formed indeneamine salt with, per part thereof, about two to four parts by weight of sodium metal and about forty to sixty parts by weight of n-propanol, and recovering 2-(p-aminophenyl)-3-methyl-6-aminoindane.
